CLAIM

The ornamental design for an accessory for a smartphone camera, as shown and described.

DESCRIPTION

FIG. 1 is a front perspective view of an accessory for a smartphone camera showing our new design;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom plan view thereof;

FIG. 8 is a perspective view thereof, showing the accessory for a smartphone camera in a folded position; and,

FIG. 9 is a perspective view showing the accessory for a smartphone camera in use.

(Continued)

The broken lines shown in FIGS. 1, 2 and 6-9 depict portions of the accessory for a smartphone camera that form no part of the claimed design. The broken lines showing environmental subject matter in FIG. 9 form no part of the claimed design.

1 Claim, 5 Drawing Sheets
